UNITED STATES PATENT OFFICE.

JOSEPH F. JAWOROWSKI, OF CLEVELAND, OHIO.

AIR PUMP.

Application filed December 4, 1922. Serial No. 604,708.

The primary object of the present invention is to provide a rotary machine adapted to compress air to a high degree and in an efficient manner. To achieve this object I provide a perfectly balanced smooth-rolling piston adapted to revolve at a high-speed within a circular compression chamber, and also provide an oscillatory member to co-act with said piston in creating and maintaining a high pressure. The machine is particularly designed to operate with a minimum of friction and to facilitate lubrication of the interior operating mechanism. The compressor is also particularly constructed to eliminate air voids and pockets; to permit accurate and convenient assembly and disassembly of the parts; to prevent leakage; to facilitate repairs and replacements; and to promote durability and a long operating life without loss in efficiency.

In the annexed drawings, Fig. 1 is a horizontal section of my improved compressor on line 1—1 of Fig. 2, and Fig. 2 is a vertical section on line 2—2 of Figs. 1 and 5. Fig. 3 is a perspective view of the rotor piston, and Fig. 4 a perspective view of the oscillatory abutment. Fig. 5 is a vertical section on line 5—5 of Fig. 7. Fig. 6 is a perspective view of the rear packing plate. Fig. 7 is a vertical section on line 7—7 of Fig. 5. Fig. 8 is a horizontal section on line 8—8 of Fig. 7, showing the lubricating device. Fig. 9 is a sectional view and elevation of the rotor shaft and rotor assembly. Fig. 10 is a vertical section on line 10—10 of Fig. 5. Fig. 11 is a perspective view of the packing ring used in the front cover plate. Fig. 12 is a side elevation of the complete compressor.

The compressor comprises a round cast-metal body 1 having a hollow rectangular base portion 2 provided with lateral supporting legs 3. The exterior of body 1 is provided with a series of heat-radiating and strengthening ribs 4, and the front side of this body is finished flat and smooth to seat a cover and bearing plate 5 opposite a circular compression chamber 6 which extends approximately half way into the body. A circular chamber 7 is provided within the rear side of body 1 opposite the vertical division wall 8 centrally within said body. A hub 9 extends from wall 8 into the rear chamber 7 and a relatively large round opening in this hub is adapted to receive a ball-

bearing ring 10 in clip seating position against an annular flange 11 extending from the end face of the hub toward the axis of the opening, see Fig. 5. The front side of wall 8 is flat and smooth except where slightly dished or recessed at 12 annularly around the front projecting end of ring 10, and this shallow annular recess 12 serves as a receiving and distributing space into which oil or grease may be introduced under pressure by way of a valved nipple 14 located in an exposed and accessible place at the circular side of body 2. In Figs. 7 and 8, this nipple is shown as communicating with a horizontal duct 15 in middle wall 8 having a discharge outlet 16 opening at right angles into annular recess 12.

The inner circular surface compression chamber 6 is constantly engaged by a rolling member 17 having the form of a flat ring of the same width as the depth of said chamber and the plane end faces 18—18 of this ring are adapted to rub against or travel in close proximity to the flat side of wall 8 and the flat face of cover plate 5, see Fig. 5, and which plate also provides a support for a ball-bearing ring 19 of the same diameter as ring 10. Plate 5 is provided with a flanged boss 20 to seat ring 19 in the same slip way as ring 10 is held and seated, and an annular flange 21 extends forwardly from plate 5 a substantial distance to provide a circular chamber 22 of relatively the same size and diameter as chamber 7. These end chambers are closed tightly, the front chamber 22 by a rabbeted plate or disk 23 removably secured to flange 21 by screws 24, and the rear chamber 7 by a packing plate 25 screwed or bolted to the rear side of body 1. Packing plate 25 is so-called because it has a screw-threaded extension 26 provided with a central shaft opening and packing recess 27, and a packing follower or gland 28 is seated within recess 27 and held adjustably in place therein by a screw cap 29 engaged with extension 26. The bottom of extension 26 is provided with a longitudinal channel 30 open at one end to the interior of screw cap 29, and the follower or gland 28 has an annular recess 31 inside which is also open to the interior of the cap by way of an outlet 32, see Fig. 5. In this way the oil or grease is prevented from escaping at the rear side of the screw cap where the exposed end of the rapidly revolving shaft 110

33 would scatter it, and is instead caused to flow into the cap and to escape through channel 30 where it can drip into a receiver if it is desirable or necessary to collect it.

5 Shaft 33 has slight enlargements 34—34 upon which separate ball-bearing rings 35—35 are sleeved with a press fit 20 so as to revolve with the shaft, and a series of steel balls 36 are confined between these rings 10 and the larger rings 10 and 19 at opposite sides of the rolling member or piston 17. A still larger ball-bearing ring 37 is slipped but not tightly into a centrally contracted portion 38 in piston 17 directly opposite and 15 surrounding a second ball-bearing ring 39 tightly fitted upon a flanged crank or eccentric portion 40 of shaft 33, and a series of heavy steel balls 41 is interposed between the two rings 37 and 39, respectively, to 20 promote a noiseless and friction-reducing drive means for the rolling piston, whereby the piston will have an orbital travel within compression chamber 6 and a constant rolling contact with the smooth circular wall 25 of said chamber. In rotating shaft 33 in a given direction the rolling piston is of course carried with it and caused to have an orbital travel in the same direction, but because its peripheral face is constantly in contact with 30 the circular wall of chamber 6 the piston is also caused to rotate on its own true axis in an opposite direction to its orbital movement. The centrifugal tendency of the piston in its rapid revolution also causes it to 35 positively engage the circular surface of the chamber and to maintain and assure a closely sealed rolling fit at all times regardless of wear at the bearings.

In order to utilize this rolling orbital movement of the piston for compressing air to a high degree and to the best advantage I employ an oscillatory member 43 having a curved abutment extension 44 adapted to project into chamber 6 in constant bearing 45 engagement with the peripheral face of the piston. The air is taken in and discharged on opposite sides of extension 44, and the intake passage 45 and the outlet port 46 are situated in such close proximity and definitely predetermined relations in respect to this extension and the circular rolling boundary for the piston that absolutely no air pockets or voids will be created in operations. Moreover to obtain a high degree of compression I have discovered that the size of the discharge port and its position in respect to the abutment is very important. Thus it should be noted in Figs. 1 and 2, that discharge port 46 is a round opening of relatively small diameter situated approximately midway between the front and rear sides of compression chamber 6, and that the axis of this discharge port meets the intersection of the two curved surfaces *a* and *b* representing the circular boundary of compression

chamber 6 and the curved pressure side of abutment 44. As piston 17 rolls toward the curved side *b* of the abutment the compression space is contracted more and more until no further compression space exists on that side of the abutment. In this movement of the piston the abutment is pressed outward to its limit when the roller is seated directly opposite the axis of the small discharge port. In this position of the parts there is absolutely no void or dead space between the abutment and piston and the port, but the port is practically open to the newly developed crescent-shaped compression chamber, and the compressed air just discharged through port 46 is prevented from returning because of the spring-pressed ball valve 48 seated in the flaring outlet end 49 of this port opposite a detachable discharge nipple 50, see Fig. 1.

The piston-engaging extremity of abutment 44 is beveled on the intake side to provide a reduced or narrow contact edge 51, and a transverse channel 52 is formed in the curved pressure side of the abutment to receive a packing strip 53 having a recessed and shouldered inner side in which a flat bow spring 54 may be confined and function to press the packing strip against the curved abutment seat 55 which has its axis or center of generation in pivot pin 56 for oscillatory member 43. This pin extends clear through the rear wall of base portion 2 where an oil or grease cup 57 may be attached thereto in an exposed and accessible position, 100 and a longitudinal oiling passage 58 extends axially through the pin and has lateral outlets 59 opening into the bore of the hub of oscillatory member 43. The forward end of this member is also provided with a semi-spherical recess 60 in which a semi-spherical head 61 is loosely seated but nevertheless held therein by a coiled wire spring 62 sleeved over the stem 63 of this head. The lower end of this spring is seated within a 110 cupped set screw 64 adjustably fixed within the closed bottom 65 of base portion 2, see Fig. 2 and therefore the spring may be compressed and permitted to expand rapidly and repeatedly without displacement or crystallization, the accommodating movement of the semi-spherical head greatly contributing to this result.

The front face of body 1 and the meeting face of cover plate 5 are provided with registering annular grooves 66 wherein a split spring ring 67 may be seated. This ring functions as a sealing member for the joint and also as a centering device for plate 5. Split balance weights 68—68 are clamped 125 to shaft 33 outside of the ball bearing and rotate in chambers 7 and 22, respectively, and these balance weights are easily reached and adjusted by merely removing the end plates 23 and 25, respectively, without dis-

turbing the main bearings. Cover plate 5 is also provided with an air intake opening 69 opposite the compartment in hollow base 2, and a perforated guard 70 having a wire 5 screen 71 at its inner flanged side is removably mounted within this opening 69, see Fig. 5. In operation shaft 33 revolves at about 1725 revolutions per minute, but the roller revolves on its own axis at a 10 much slower speed. Two hundred and fifty pounds pressure and higher can be obtained from this rotary compressor, using a cooling jacket, but the compressor can be operated continuously without a cooling 15 jacket and compress air from one hundred and seventy-five to two hundred pounds pressure.

What I claim, is:

A rotary air compressor, comprising a body having a circular air-compressing 20 chamber open at one side thereof and provided with air intake and discharge ports, a movable cover plate enclosing the open side of said chamber, said body and cover plate having circular registering grooves in their 25 meeting faces, a split spring ring mounted within said grooves, a rolling air-compressing member within said chamber, and a movable abutment extending into said chamber intermediate said intake and discharge ports. 30

In testimony whereof I affix my signature hereto.

JOSEPH F. JAWOROWSKI.
